UNITED STATES PATENT OFFICE.

JOHN EDWARDS, OF NEW YORK, N. Y., ASSIGNOR TO WILLIAM CRAWFORD,
OF SAME PLACE.

DESIGN FOR A DRESS-SHIELD.

SPECIFICATION forming part of Design No. 33,161, dated September 4, 1900.

Application filed August 4, 1900. Serial No. 25,950. Term of patent 7 years.

To all whom it may concern:

Be it known that I, JOHN EDWARDS, a resident of the borough of Manhattan, in the city, county, and State of New York, have invented and produced a new and original Design for Dress-Shields, of which the following is a specification.

In the accompanying drawings, forming a part hereof, Figure 1 represents a side view of a dress-shield; and Fig. 2 a perspective view thereof, showing my new design.

As shown, the leading or material feature of my design consists in the dress-shield provided at the forward upper corner with an elongated extension or tip (indicated by the letter A) having substantially-parallel sides for a portion of its length, the tip being cut

off bluntly at the end, and provided at the rear upper corner with a relatively-shorter pointed crescent-like tip, (indicated by the letter B.)

Having described my invention, what I claim as new, and desire to secure by Letters Patent, is—

The design for a dress-shield, as herein shown and described.

In testimony whereof I have signed my name to this specification, in the presence of two subscribing witnesses, this 1st day of August, 1900.

JOHN EDWARDS.
